UNITED STATES PATENT OFFICE.

JOHANN VOGT, OF GÖPPINGEN, GERMANY.

PROCESS FOR DRYING BOARDS AND THE LIKE.

1,134,247.

Specification of Letters Patent. Patented Apr. 6, 1915.

Application filed October 25, 1913. Serial No. 797,182.

To all whom it may concern:

Be it known that I, JOHANN VOGT, a citizen of the German Empire, residing at Göppingen, Wurttemberg, Germany, have invented certain new and useful Improvements in Processes for Drying Boards and the like, of which the following is a specification.

The splitting and cracking of freshly sawed boards, planks deal boards and wood in general during drying has ever been felt to be a defect, arising partly from the unequal density of the wood and partly from the gradual process of drying of the wood during its progress from the surface to the center. If a freshly cut board, taken from the center of a tree, is laid up for drying, one may observe, that it contracts as the drying process goes on, not only as to its width but also in its length, which latter is not generally known. This contraction lengthwise of the wooden fibers, however, does not occur uniformly but it is more considerable near the edges than in the center. Moreover it is found, that the cells of trunks, left uncut for any length of time, will have dried much quicker near the bark than those in the center of the trunk, producing likewise an unequal contraction of the volume. The result of such irregular reduction of the volume and contraction of the fibers must naturally be a certain tension in the wood, which will find its release by the cracking of the boards as soon as the limits of elasticity are exceeded. As a result a board is liable to split into two crescent-shaped parts—the interior one being smaller by 5% than the exterior one, which consists of heart-wood.

The purpose of this present invention is to prevent the formation of these air-cracks (drying cracks) on the face as well as within the boards.

If we are able to retard the drying of the layers near the bark which are more liable to contraction than those near the center, than the latter will chiefly contract in a longitudinal direction of the fibers and attain the desired degree of dryness without any bending of the wooden fibers, because the central layers form one whole in such case, which contract mutually or toward each other, while the exterior soft layer of wood is forced to contract toward the rigid center layer.

Figure 1 shows the arrangement of the

supports when the air current enters at the ends of the boards. Fig. 2 shows the arrangement when the air current enters at one of the longitudinal sides. Fig. 3 shows the boards superposed.

The purpose of this present invention is to be attained by placing along the boards, between them a number of small ledges (a) as supports, which at the ends of the boards are brought into connection with shorter ledges (b) and at an acute angle as shown on the diagram.

By means of the parallel supporting ledges a (Fig. 1) it is intended to force the air along the boards instead of transversely across the boards. The transverse ledges b have the effect, that the air does not brush past the entire width of the boards, but chiefly and without hindrance passes over them along the center. On the other hand it will be found that the air is banked up in the cells, formed by the transverse ledges, with the result that less moisture is being absorbed from the outside of the boards in a longitudinal direction than by the shorter current of air which passes over the center of the boards longwise.

According as the transverse ledges are placed, the outer parts of the boards will take double the time or even longer for a complete desiccation than the center parts. But there is still another peculiarity of the supporting ledges to be referred to which is eminently calculated to further the aims in view, viz the property of these staple ledges a and b of directly hampering their drying influence, which arises from the manner of placing them on the longitudinal faces of the boards, or vice versa, whereby not only the covered spots themselves but also the longitudinal fibers of the wood on either side are checked in drying.

If, for instance, some beech boards are taken off the transverse supporting ledges, upon which they had rested already for some time, before being fully dry, it will be observed that the boards are still more or less damp in those places, and near them, on which they had rested, whereas the more distant spaces between the staple ledges are fully dry. This may readily be explained by the fact, that the air is prevented from exerting its drying influence upon all such places of the boards which are covered by staple ledges. In the same way does the humidity contained in the staple ledges themselves retard the dry-

ing of the places nearest to them on the boards; besides this it should be noted that the damp in the staple ledges *a* and *b* is continually being renewed by the action of rain etc., with the effect, that the drying of the surrounding layers of wood is likewise retarded. This peculiarity of the staple ledges, which hampers the drying of the longitudinal sides of the boards, contributes to the fact, that the edges of the boards (near the bark *c*) as well as the partially covered lateral layers of the boards, which are protected by the transverse staple ledges, are still far from being dry while the center of the board has become dry and rigid, because protected from all outside moisture (rain etc.) and continually exposed to the current of air passing along it.

It is also possible to retard complete drying of parts near the bark more or less by giving to the staple ledges *a* and *b* a corresponding form reducing the places of contact. In like manner one may protect the outside of the boards, deals etc. in a rational way from a too speedy drying by regulating the distances of the several transverse staple ledges in accordance with the percentage of water, hardness and structure of the wood to be dried. On the other hand one may contrive to accelerate or retard the drying of the center layer, according to necessity, by forming a wider or a narrower air channel with larger or smaller apertures in the longitudinal sides of the board (along the center layer.) In the place of wooden ledges one may employ strips of cardboard or duly shaped stencils.

As shown by Fig. 2 the longitudinal staple

ledges may be placed in such a way that the air-channel begins or ends either at the front faces or at the sides of the boards.

What I claim and desire to secure by Letters Patent is:

1. The herein described process of drying boards, beams and the like which consists in drying the center portions before drying the outer portions. 45

2. The herein described process of drying boards, beams and the like which consists in subjecting the board, beam or the like to the action of a current of air and retarding the drying of the outer portions. 50

3. The herein described process of drying boards, beams and the like which consists in causing an air current to traverse the board, beams or the like in the direction of its length and impeding the progress of the current adjacent the outer portions of the board beam or the like. 55

4. The herein described process of drying boards, beams and the like which consists in placing the boards, beams or the like in superposed relation and spaced from one another by spaced supporting members positioned adjacent their outer portions whereby longitudinally extending passages are formed between adjacent boards, and causing a heated medium to pass through said passages and into the spaces between said supporting members. 60 70

In testimony whereof I affix my signature in presence of two witnesses.

JOHANN VOGT.
